UNITED STATES PATENT OFFICE.

ARTHUR A. FULLER, OF PROVIDENCE, RHODE ISLAND, ASSIGNOR TO
HOMER MERRIAM, OF SPRINGFIELD, MASSACHUSETTS.

BOOK-SUPPORT.

SPECIFICATION forming part of Letters Patent No. 319,899, dated June 9, 1885.

Application filed July 19, 1884. (No model.)

To all whom it may concern:

Be it known that I, ARTHUR A. FULLER, a citizen of the United States, residing at Providence, in the county of Providence and State 5 of Rhode Island, have invented certain new and useful Improvements in Book-Supports; and I do declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Figure 1 of the drawings is a representation of this invention, and shows the upper part in vertical section. Fig. 2 is a side view of the support folded. Fig. 3 is a horizontal section taken on the broken line *x* *x* in Fig. 1.

20 This invention has relation to folding book-supports of light and portable character; and it consists in the construction and novel arrangement of devices, as hereinafter set forth, and pointed out in the appended claims.

25 In the accompanying drawings, the letter *A* designates the arm, on which the holder *B* rests, said arm having a slide-clamp, *C*, adapted to engage the base of the holder, and secured by means of a thumb-screw, *a*. The arm *A* consists of an inner section, *D*, which is, by 30 means of the hinge *E*, connected to a rotary head-block, *F*, and an outer section, *G*, to which the clamp *C* is connected, and which is pivoted to the inner section, as shown. The

35 barrel portion of the hinge *E* projects beyond the side of the head-block *F*, so that when the arm *G* is extended it can be turned over in position to hang down alongside the stem of the support. The stem portion of the support consists of two flat sections, *H* and *I*, which are connected by slide-straps *b*, and are held in relative position after adjustment by a 40 rack, *c*, consisting of transverse pins in a central longitudinal slot of the upper section, *I*, and a spring-arm, *d*, attached to the lower section, *H*. The upper end of the sliding or rack section *I* is provided with an enlargement or bearing, *J*, on the top of which is the washer *e*, through which passes the pivot-screw *g* of

the head-block *F*. The lower stem-section, *H*, 50 is secured to a foot-block, *K*, to the bottom of which is fastened a weight, *L*, adapted to counterbalance the weight of the book on the book-rest and prevent the stand from being easily tipped over. The foot-block *K* is rectangular or prismatic. 55

To one side of each vertical face *h* is pivoted, by a screw, *k*, an elongated leg, *N*, in such a manner that its plane of movement is parallel to that of the face *h*. It is therefore always in 60 contact with said face, and is braced thereby. To the other side of the face *h* is secured a stop, *l*, which is preferably a nut, *n*, capable of adjustment, so that it can be turned to receive the bearing edge *m* of the leg-bar *N* squarely 65 when said leg-bar is turned outward obliquely in supporting position.

When it is desired to fold the stand, the arm *A* is turned in pendent position, the upper stem-section, *I*, is pressed downward alongside 70 the lower section, *H*, and the leg-bars *N* are turned upward alongside the stem. The stand is thus readily folded in small compass, and may be easily carried or packed for transportation. 75

I am aware that it is not new to provide two sliding stem-sections for supporting a rack, and that racks for holding music have been composed of a series of pivoted bars and the whole hinged to the upper end of a stem, and 80 therefore do not claim such devices, broadly; but,

Having described this invention, what I claim, and desire to secure by Letters Patent, 85 is—

1. In a book-support, the holder-arm *A*, consisting of the inner section, *D*, hinged to the head-block *F* of the stand, and the outer section, *G*, pivoted to said inner section and carrying the slide-clamp, whereby the holder 90 is attached to the arm, substantially as specified.

2. The combination, with the upper stem section or support, of the washer *e*, pivot-screw *g*, head-block *F*, hinge *E*, having its barrel 95 portion projecting beyond the side of said head-block, and the flat arm connected by said hinge to said head-block, whereby the said

arm may hang in folded position alongside said stem section or support, substantially as specified.

3. In a folding portable book-support, the combination, with the stem and its arm, of the counterbalancing weight connected to the foot of said stem and the leg-bars extending from said foot, substantially as specified.

In testimony whereof I affix my signature in presence of two witnesses.

ARTHUR A. FULLER.
